INDICATING MEANS

Harold C. Mattes and Louis J. Wronke, Chicago,
Ill., assignors to Belmont Radio Corporation,
Chicago, Ill., a corporation of Illinois

Application July 24, 1941, Serial No. 403,892

6 Claims. (CL 116—124.1)

This invention relates generally to indicating means adapted for use on a cabinet or housing for apparatus including indicating mechanism, and in particular to indicating means having a transparent dial member arranged to utilize a panel of the cabinet as a background.

In the cabinets usually provided for apparatus having indicating mechanism, the front or face panel of the cabinet is generally formed with openings therein for receiving the indicating elements such as the needle or dial. Thus in cabinets for radio receiving apparatus the dial member, which has the various broadcasting bands arranged thereon, is received in an opening which usually extends over an appreciable part of the face or control panel. As a result the over-all cabinet structure is somewhat weakened by the greatly reduced ability of the control panel to resist warping or cracking. This disadvantage is particularly objectionable in the cabinets for portable radios in which the opening for the dial member usually covers the greater part of the control panel. Also the cost of cutting the dial opening and the cost of the usual dial parts appreciably increases the over-all cost of the radio.

It is an object of this invention, therefore, to provide in combination with the panel of a housing for apparatus including indicating mechanism, a transparent dial member which utilizes such housing panel as a background for showing up the indicia thereon.

A further object of this invention is to provide indicating means for radio receiving apparatus which is mounted on but spaced from the control panel in a manner to entirely eliminate the need for any opening in the panel for the dial member.

A feature of this invention is found in the provision with the panel of a housing for apparatus having indicating mechanism of a transparent dial member, supported on the panel but spaced therefrom, with the pointer or indicator for the dial member being movable between such member and the panel, the panel constituting a background for the dial member and extending beyond the outer edges thereof so as to be visible both through and to the sides of the dial member.

Another feature of this invention is found in the provision with the panel of the housing for apparatus having indicating mechanism, of pre-assembled indicating means adapted to be mounted on the panel as a unit and including a transparent dial member spaced from the panel but utilizing such panel as a background for the indicia thereon. An indicating needle for the dial member is supported in the unit for movement across the dial member and between the dial member and the panel, the needle being operatively connected with the apparatus in the

cabinet by means adapted to extend through the panel.

Further objects, features, and advantages of this invention will become apparent from the following description when taken in connection with the accompanying drawings in which:

Fig. 1 is a front view of the control panel of a radio cabinet showing the invention thereon;

Fig. 2 is a fragmentary rear view of the invention looking from the rear and at the left as viewed in Fig. 1;

Fig. 3 is a fragmentary sectional view as seen along the line 3—3 in Fig. 2;

Fig. 4 is a fragmentary detail view taken along the line 4—4 in Fig. 2;

Fig. 5 is a perspective view of a retaining member for the dial member;

Fig. 6 is a fragmentary view of the control panel for a radio cabinet showing a modified form of the invention;

Fig. 7 is illustrated similarly to Fig. 5 and shows the invention as applied to a clock; and

Fig. 8 is a rear perspective view of the invention showing the transparent dial and indicating needle therefor preassembled as a unit with an escutcheon plate for a radio cabinet.

Referring to Fig. 1 the invention is illustrated with a control panel 10 for the cabinet of a radio receiver. The control panel 10 is provided with a one-piece escutcheon plate 11, which is extended longitudinally thereof and is composed of a plastic material such as "tenite" or the like. The escutcheon plate 11 has a body portion 15 of substantially rectangular form, the control means for the radio receiver such as control knobs 12 and 13 and push button units 14 being suitably arranged in the lower portion thereof. As is clearly shown in Figs. 3 and 4 the plate 11 is of hollow construction with the end portions 16 thereof being of arcuate form and turned inwardly toward the panel 10 so that the open side of the plate is in mating engagement with the panel 10. Screws 17 are extended through the plate 11 and secured in the panel 10 to mount the plate thereon in an obvious manner.

At the top of each end portion 16 as viewed in Fig. 1, there is provided a railing portion 18 which projects upwardly from the body portion 15 of the escutcheon plate 11. Each railing portion 18 is comprised of a pair of longitudinally extending rail elements 19 connected together by post members 21 and 22. The post member 22 is provided with an aperture 23, to be later noted, with the post 21 and the rail elements 19 inwardly of the post 22 being cut back to provide a flat recessed or bearing portion 24 (Fig. 4) defined by a shoulder 26 at the post 23. The recessed or bearing portions 24 are adapted to support a transparent dial member 27 of substantially rectangular shape and of a length

adapted to fit between the shoulders 26 in the projecting or railing portions 18.

The dial member 27 (Figs. 2 and 3) may be composed of glass or other transparent material, and extends within the body portion 15 of the plate 11, which is provided at each end 16 thereof with an integrally formed inner shelf or extension 28 adapted to be received in a corresponding notch 29 in the dial member 27. From a consideration of Figs. 2 and 4, it is evident that the dial member 27 is held against movement sideways and forwardly of the plate 11 by virtue of its position in the recessed portions 24, and against movement vertically of the plate 11 by the engagement of the projections 28 and the notches 29. The dial member 27 is retained in this position on the plate 11 and against movement rearwardly thereof by means of retaining plates 31, one of such plates being provided at each end 16 of the escutcheon plate.

As shown in Fig. 5 each retaining plate is comprised of a substantially flat body portion 32 having an end 33 of reduced section. The body portion 32 is integrally formed with a laterally extending peripheral rim or spacing flange 34 which is open at the end 33. The end 33 is provided with an aperture 36 corresponding to the aperture 23 in the post member 22, the retaining member 31 being secured to the post 22 and against the plate member 27 by a rivet or securing member 37. Referring to Figs. 4 and 5 it is seen that the peripheral rim 34 faces the panel 10 while the body portion 32 is against the dial member 27, the body portion as indicated at 38 being recessed to provide for a slight movement of the retaining member 31 in its retaining position into alignment with the panel.

It is seen, therefore, that the dial member 27 is supported entirely on the escutcheon plate 11 and held in a fixed position thereon. As shown in Fig. 1 the member 27 has band wave indicia 39 longitudinally arranged thereon between the railing portions 18. Although only indicia for one band wave is illustrated it is to be understood that any number of such indicia may be used since it is apparent that additional indicia can be arranged longitudinally of the plate 27 so as to extend above the railing portions 18 if necessary. Since the dial member 27 is composed of a transparent material, the panel 10 is clearly visible therethrough so as to constitute a background or screen for showing up the indicia 39 on the dial 27. The panel 10 is thus utilized with the dial member 27 to provide an over-all pleasing appearance of the radio, the panel being visible both through the member 27 and about the outer edges thereof. In the event a magic eye, indicated at 41, is used it also is clearly visible through the dial member. A particular backing for the dial member is thus entirely eliminated and an attractive indicating means is assured because of the natural blending of the cabinet panel 10 with the rest of the cabinet structure.

The pointer or indicator 42 for the dial member 27 has the lower portion 43 thereof (Fig. 3) extended through an opening 44 in the panel 10 and is operatively supported on a portion of the radio apparatus (not shown) for movement longitudinally of the member 27 and between such member and the panel 10. Since the dial member 27 is supported solely on the escutcheon plate 11 it is seen that only the pointer 42 and radio control elements are extended through the panel 10 so that only a relatively small part of the panel 10 is provided with openings. By virtue of this

substantially solid construction of the panel 10, its ability to resist warping and cracking is greatly increased.

As illustrated in Fig. 8 the pointer 42' can also be supported entirely on the escutcheon plate 11 so as to further eliminate the opening 44 in the panel 10. Parts in Fig. 8 corresponding to the like parts in Fig. 1 are indicated by like reference characters primed. In the assembly of the needle 42' with the escutcheon plate 11' there is provided a bracket 45 having a bearing portion 46 at each end thereof for rotatably supporting a corresponding one of the axes 47 and 48 for the control knobs 12' and 13', respectively. Pulleys 49 and 51 are mounted on the axes members 47 and 48, respectively. The bracket portion 50 intermediate the ends 46 thereof is of substantially flat form and in interlocked but slidable engagement with a base portion 55 on the needle 42'. A belt or flexible connecting member 52 is extended about the pulleys 49 and 51 and is connected as at 53, with the base 55 of the needle 42'. Assuming the control knob 12' to be the manual tuning knob, and the control knob 13' to be the off and on control for the radio, the pulley 51 would be mounted on the axis 48 so as to be rotatable relative thereto. Thus on turning of the knob 12' the pulley 49 would drive the pulley 51 with the belt 52 moving the needle 42' across the dial member 27' in an obvious manner. The inner ends of each of the axes members 47 and 48 may be slotted to provide for their operative connection with the radio apparatus through the panel 10.

In Fig. 6 the dial member 27a is illustrated as comprised of a circular dial face 56 and a substantially rectangular base or supporting portion 57 integrally formed therewith. The base portion 57 is positioned in a recessed portion 54 formed in the escutcheon plate 11a, and is held in a fixed position thereon by means of the projections 28a, and retaining members 31a in a manner similar to that described above for the like parts in Fig. 1. With the dial member 27a thus supported the circular dial face 56 extends upwardly from the escutcheon plate 11a spaced from the panel 10a of the radio cabinet but with such panel completely visible behind all portions of the dial face. The indicia 39a are peripherally arranged about the dial face 56 so that the panel 10a serves as the background for making these indicia visible. The indicator needle 58 is mounted for rotation between the dial member 27a and the panel 10a with the axis 59 thereof being extended through the panel 10a. The control knobs 12a and 13a are extended through both the panel 10a and the escutcheon plate 11a, which is secured to the panel by the screws 17.

In Fig. 7 the invention is illustrated as being applied to a clock having a face panel 61 and hand members 62 suitably supported on an axis member 63 extended through the face panel 61. The dial member 27a is similar in all respects to the dial member 27a in Fig. 6, the base portion 57 thereof being supported in an escutcheon plate 11b having dial member engaging projections 28b and retaining members 31b assembled in the manner previously described for the corresponding parts in Fig. 1. The numeral indications 64 are peripherally arranged about the face portion 56, the panel 61 constituting the background for the dial face 56. The hand members 62 and 63 are rotated between the dial member 27a and the panel face 61, which is visible through

the member 27a and extends outwardly beyond the outer edges thereof.

From a consideration of the above description and drawings, therefore, it is seen that the invention provides the combination of a transparent dial member with a panel portion of a cabinet in which the panel per se constitutes the background for the dial member, so that any openings in the panel for receiving the dial member are entirely eliminated. It is evident, of course, that the dial member may be used in combination with panels of varying size since the dial support is mounted directly on the panel, with the panel extending outwardly from the edges of the dial. Because of the transparent character of the dial member it is obvious that the indicia arranged thereon can be viewed equally well if arranged directly on the panel member, the glass member in such case serving solely as a cover or face. Also, by virtue of the spaced relation between the dial members and the housing panel, and the translucent composition of the escutcheon plates, various attractive lighting effects utilizing glow lamps and the like may be used in conjunction with the invention with advantageous decorative results.

Although the invention has been described with reference to several preferred embodiments thereof it is to be understood that it is not to be so limited since alterations can be made therein which are within the full intended scope of the invention as defined by the appended claims.

We claim:

1. In radio receiving apparatus having a cabinet with a control panel, an escutcheon plate mounted on said panel longitudinally thereof, a vertically extending transparent member positioned longitudinally of said control panel and supported at the bottom thereof on said escutcheon plate, said member having a dial portion extending upwardly from said plate in a spaced relation with said panel and free of said panel at the marginal edges thereof, said dial portion having band wave indicia arranged longitudinally thereof, an indicator for said dial portion spaced therefrom, means carried on the back of said escutcheon plate and within the peripheral confines thereof for supporting said indicator for movement between said dial member and panel and longitudinally of said dial face, with said panel constituting the sole background for said dial portion and indicator, and being visible through said dial portion and outwardly from the marginal edges thereof.

2. In radio receiving apparatus having a cabinet with a control panel, an escutcheon plate mounted on said panel, a transparent dial member supported on said plate having a portion carried on said plate and another portion extended from said plate in a spaced relation with said panel, with the space between said panel and said another portion being open at the marginal edges of said another portion, said panel constituting the sole background for said dial member and being visible through said another portion and outwardly from the marginal edges thereof.

3. In apparatus including indicating mechanism, a cabinet for said apparatus having a panel portion, a transparent portion, with one of said two portions having indicia thereon, means carried on said panel portion for supporting said

transparent portion in a spaced relation with said panel portion, said transparent portion having a portion of the marginal edge thereof carried on said supporting means, with the space between said transparent portion and panel portion being open over the remaining marginal edge of said transparent portion, an indicating member associated with said indicia movable within said space, said panel portion constituting the sole background for said transparent portion and being visible through said transparent portion and to the outside of said remaining marginal edge, with said remaining marginal edge defining the outline of said transparent portion against said panel portion.

4. In combination with a panel portion of a cabinet for apparatus including indicating mechanism, a transparent dial member, means supporting said dial member on said panel portion in a spaced relation therewith, with said supporting means being connected with said dial member over only a portion of the marginal edge thereof, with the remaining portion of said marginal edge being unsupported and extended from said supporting means, with the space between said dial member and panel portion being open at said remaining portion of the marginal edge, an indicator associated with said dial member movable in the space between said dial member and panel portion, said panel member being visible through said dial member and outwardly from the unsupported marginal edge of said dial member, with said unsupported marginal edge outlining said dial member against said panel portion.

5. In radio receiving apparatus having a cabinet with a control panel, an escutcheon plate mounted on said panel, and a transparent member having a portion supported on said plate, and a dial portion free of said plate and extended therefrom in a spaced relation with said panel, with the marginal edge of said dial portion being within the confines of said panel and the space between said transparent member and panel being open at said marginal edge, said panel serving as the sole background for said dial portion and being visible therethrough, with said marginal edge defining the outline of said dial portion against said panel background.

6. In apparatus including indicating mechanism and a cabinet with a panel portion, a pre-assembled escutcheon unit including frame means mounted on said panel portion and a transparent member arranged in a spaced relation with said panel portion, said transparent member having a portion supported on said frame means and a dial portion extended from said frame means in a spaced relation with said panel portion and free of said panel portion, an indicator for said dial portion movable within said space and visible through said dial portion, with said panel portion being visible through said dial portion and outwardly from the marginal edge of said dial portion, with the marginal edge of said dial portion outlining said dial portion against said panel portion, and means movably supporting said indicator carried on said frame means within said space and within the peripheral confines of said frame means.

HAROLD C. MATTES.
LOUIS J. WRONKE.
